UNITED STATES PATENT OFFICE.

JULIAN HUGH THOMAS, OF HAMILTON, CANADA.

OLIVER.

SPECIFICATION forming part of Letters Patent No. 728,143, dated May 12, 1903.

Application filed August 12, 1902. Serial No. 119,423. (No model.)

To all whom it may concern:

Be it known that I, JULIAN HUGH THOMAS, a citizen of Canada, residing at Hamilton, in the Province of Ontario and Dominion of Canada, have invented new and useful Improvements in Olivers, of which the following is a specification.

My invention relates to improvements in olivers; and it consists in the peculiar and advantageous construction hereinafter described, and particularly pointed out in the claim appended.

In the accompanying drawings, Figure 1 is a side elevation of the construction constituting the preferred embodiment of my invention with the upper portion of one of the standards broken away. Fig. 2 is a transverse section taken on the broken line 2 2 of Fig. 1 with a portion of the hammer-helve broken away, and Fig. 3 is a detail plan with a portion of the hammer-helve broken away.

Similar letters of reference designate corresponding parts in all of the several views of the drawings, referring to which—

25 A is the base of my improved oliver; B, standards fixed to and rising from the base; B' B', braces connected to the base and standards; C, a pedal-lever fulcrumed at *a* on a support *b*, connected to the base; D, the head, 30 and E the helve, of a hammer; F, a rock-bar interposed between the standards and having trunnions *c* at its ends journaled therein; G, a plate connected to or formed integral with the rock-bar, preferably the former, and having the outwardly-extending lateral arm *d* at its forward end; H H, shackles by which the hammer-helve is preferably connected to the 35 rocking support formed by the bar F and plate G; I, a connection interposed between the 40 pedal-lever C and the arm *d* of the hammer-support, and made up, by preference, of a bell-crank lever *e*, fulcrumed on one of the standards B and having its arms connected by a link *f*, a link *g* connecting the lower arm 45 of lever *e* and the pedal-lever and a sectional rod *h* connecting the upper arm of the lever *e* and the hammer-helve and having its sections connected by a turnbuckle, as shown; J, a resilient bar connected at one end to the 50 base A and adapted to normally rest in the position shown in Fig. 1; K, a coiled spring interposed between and connecting the free

portion of said resilient bar and the base A, and L one or more coiled springs interposed between and connected with the rear end of 55 the hammer-helve and the forward free portion of the bar J. The hammer-head D may be of any suitable type without involving a departure from the scope of my invention; but I prefer to make it of cast-iron and to 60 provide it with a face *i* of steel, the said face being in the form of a block and being removably secured in the head, this latter to permit of it being replaced with a block of different shape when desired. 65

My improved oliver is designed more particularly for use in conjunction with an ordinary anvil, and in practice it is placed at one side of the anvil, so the hammer-head D will strike on the same and so that the pedal-lever C, which is preferably of sufficient length, will extend beyond the side of the anvil remote from the standards B. This arrangement will obviously enable a mechanic standing at the opposite side of the anvil 70 with reference to the standards B to operate the hammer and at the same time conveniently manipulate the work on the anvil. 75

The parts of the oliver are shown in their working positions, and it will be readily observed that when the pedal-lever C is depressed the hammer-head D will be thrown downwardly, also that when pressure is removed from the pedal-lever the hammer head and helve will be quickly returned to 80 the position shown in Fig. 1 by the springs connected therewith. It will also be observed that when it is not desired to use the oliver the hammer may be thrown back, so that its head rests above and in rear of the vertical 85 median line of the standards B and the rear end of its helve rests between the lower portions of the standards. When the hammer is thrown back, as described, the arm *d* of the plate G will bring up against the upper end 90 of one of the standards B and serve as a stop to limit the backward movement of the hammer. The hammer will remain of itself in the idle position stated; but it may be returned to its working position by simply 95 swinging its head forwardly.

In virtue of the free portion of the resilient bar J being connected with the base A by the coiled spring K and with the hammer-helve

by one or more coiled springs L it will be observed that subsequent to a downward movement of the hammer-head said head will be caused to rebound to a position above or beyond its normal position, so that its own weight will add to the power of the succeeding blow. It will also be observed that the resilient bar and the springs connecting the same to the base and the hammer-helve constitute a very strong and durable means for raising the hammer-head subsequent to downward movements thereof.

I have entered into a detailed description of the construction and relative arrangement of parts embraced in the present and preferred embodiment of my invention in order to impart a full, clear, and exact understanding of the same. I do not desire, however, to be understood as confining myself to such specific construction and relative arrangement of parts, as such changes or modifications may be made in practice as fairly fall within the scope of my invention as claimed.

Having described my invention, what I claim, and desire to secure by Letters Patent, is—

In an Oliver, the combination of a base,

standards fixed on and rising from the base, a hammer-support interposed between the standards, and having trunnions journaled in the same, and also having a lateral arm on its forward portion, arranged when the hammer-head is swung rearwardly beyond the vertical plane of the trunnions, to bring up against the upper end of one of the standards, a hammer-helve arranged on and connected to said support, a pedal-lever fulcrumed on a support rising from the base, a connection between said lever and the lateral arm of the hammer-support, a resilient bar connected at one end to the base, a coiled spring interposed between and connecting the free portion of said bar and the base, and one or more springs interposed between and connecting the free portion of said bar and the rear portion of the hammer-helve.

In testimony whereof I have hereunto set my hand in presence of two subscribing witnesses.

JULIAN HUGH THOMAS.
